ANTIJIMMY DEVICE FOR PADLOCKS

Roger L. Owen, Milwaukee, and Daniel J. Foote, Wauwatosa, Wis., assignors to Master Lock Company, Milwaukee, Wis., a corporation of Wisconsin

Filed Oct. 6, 1967, Ser. No. 8,885

Term of patent 14 years

(Cl. D50—8)

Fig. 1

Fig. 2

Fig. 3

Fig. 4

FIG. 1 is an end and side perspective view of an anti-jimmy device for padlocks showing the design, the dotted line showing of the shackle being for illustrative purposes only;

FIG. 2 is a front view of the anti-jimmy device;

FIG. 3 is a top plan view thereof; and

FIG. 4 is an inverted plan view of the anti-jimmy device.
We claim:

The ornamental design for an anti-jimmy device for padlocks, as shown and described.
